UNITED STATES PATENT OFFICE

RANDAL E. TALLEY, OF IRWIN, PENNSYLVANIA

ROTARY HEARTH FURNACE

Application filed February 18, 1931. Serial No. 516,611.

This invention relates to rotary hearth furnaces, more especially to the hearth and wall structures of such furnaces, and it is among the objects of this invention to provide rotary furnaces in which the hearth shall be free to expand without interfering with the side wall forming the furnace chamber.

A further object of the invention is to provide a wall structure of especially designed tile which shall prevent displacement of the tile due to expansion of the furnace wall.

Heretofore, it was customary to construct the hearth of a rotary furnace so that its outer periphery was within the limits of the inner dimension of the annular wall structure, clearance being provided to prevent interference of the rotating hearth when the latter expanded due to high temperature of the furnace chamber.

In this type of furnace, the upper portion of the hearth expands due to high temperature, the blocks of refractory material, of which the hearth is constructed, do not return to their original position because there is no external force or pressure available to return them to this position. As a consequence of this expansion, cracks appear between the blocks when the hearth is subjected to cooling, and the cracks are filled with dirt and small particles of refractory so that when the hearth is again brought to a high temperature it will expand to a still larger diameter until in the course of time, the progressive expansion of the hearth is such as to render it inoperative.

Such expansion has been experienced to be as much as to take up four inches of clearance between the hearth and the inner dimension of the furnace wall, and the present invention is designed to overcome the aforementioned difficulties.

In accordance with the present invention the rotary hearth is below the side wall, not encompassed by it, and is, therefore, free to expand without interference with the side wall structure. Furthermore, the outer periphery of the hearth is exposed to atmospheric temperature permitting the use of

curb angles or other suitable retaining means to hold the hearth refractories in position.

In the accompanying drawings constituting a part hereof and in which like reference characters designate like parts, Figure 1 is a sectional elevational view of a rotary furnace embodying the principles of this invention; Figure 2 a diagrammatic view illustrating the tile structure of the side wall of the furnace; and Figures 3 and 4, 5 and 6, 7 and 8, and 9 and 10 are side and end elevational views, respectively, of the tile employed in the construction of the side wall.

With reference to Figure 1 of the drawings, the structure therein illustrated comprises a hearth 1 mounted on a casting generally designated at 2, having a gear-tooth rack 3 and a ball race 4 by means of which it is supported on ball bearings 5 which are mounted on a supporting base 6.

The hearth is rotated by a gear drive generally designated at 7, of which a beveled gear pinion 8 meshes with teeth 3 of the frame 2, the gear being actuated through suitable reduction gearing 8a, and a motor generally designated at 9.

Above the hearth 1 is a side wall and roof construction, 10 and 11, respectively, which form the furnace chamber 12. The side wall 10 consists of a plurality of tile blocks which are supported by a sheet metal housing or shell 13 having a flange 14 projecting inwardly at the bottom to prevent the tile blocks from slipping downwardly. The shell 13 of the side wall is supported on pillars 15 which are offset to provide sufficient clearance for a sand seal 16 to prevent the escape of heat from the furnace chamber and the ingress of air to the interior thereof.

The sand seal consists of a structural element 17 of substantially Z shape which is attached to the shell 18 of the hearth to form a channel shaped groove which is filled with sand in which a vertically depending flange member 19 projects from wall 10 to form the seal.

The side wall 11 of the furnace may be

constructed of tile blocks as shown in Figures 2 to 10 of the drawings, the tile A comprising the main body portion of the wall, this block being beveled at the corner as shown at 20, to provide a skewback for the dome arch 11. A recess 21 is cut in the corner opposite the corner 20 so that the supporting ledge 14 at the bottom of the furnace shell 13 is protected from direct radiation of heat in the furnace chamber. Tiles B and C are wedge shape pieces of the same general form as tile A, but cut to the shape necessary to provide flue openings 22, shown by dotted lines in Figure 1. Tile B rests against the furnace shell 13 and is self-supporting in the same manner as the tile A. Tile D is essentially a counterpart of tile A except that it is provided with a recess 23 along the inner edge which is shaped to receive tile C after the manner shown in Figure 2.

The reinforcing angle at the bottom of the tile structure provides a supporting ledge for the circular wall and the dome arch which is carried on the circular wall, the tile structure in turn being supported by the members 15.

From the construction herein described, it is apparent that the tile comprising the furnace wall cannot move downwardly on account of the ledge which supports them; that they cannot move outwardly on account of the retaining steel shell 13 which encircles them; and that they cannot move inwardly on account of their wedge shape, thus rendering the wall entirely self-supporting to permit the hearth to rotate freely beneath the wall as shown.

In Figure 1 a portion of a material charging and discharging door structure is shown in elevation, and to provide for the support of tile above the door and not impair the strength of the furnace wall, a heavy metal yoke 25 is provided, this yoke being preferably a single casting or forging with inwardly projecting flange which engages the tile in a manner similar to the ledge 14 of the outer shell 13.

Furnaces of the type described herein have a wide application for the heating of billets, plates, or other small parts prior to forging, rolling or pressing.

Although one embodiment of the invention has been herein illustrated and described, it will be obvious to those skilled in the art that various modifications may be made in the details of construction without departing from the principles herein set forth.

I claim:

1. A rotary furnace structure comprising a plurality of wedge shape tile having their joints disposed radially of the furnace chamber, some of the tile constituting full wall sections and other of said tile having re-

cessed sides for receiving complementary shaped sides of adjacent tile to form vertical flues having outlets at the bottom of the inner wall, metal sheathing surrounding said tile and constituting a support for the wall, the bottom of the sheathing extending partially below the tile, a plurality of standards mounted in spaced relation and adapted for mounting the tile supporting sheathing in spaced relation with the furnace floor, and a rotary hearth disposed in spaced relation below and extending to the outer limit of the furnace wall out of contact therewith.

2. A rotary hearth furnace comprising in combination a circular hearth, side wall and roof structure forming a heating chamber, the side wall and roof structure being supported above the hearth and the side wall having flues extending vertically therein and communicating at their lower end with the interior of the heating chamber adjacent the upper surface of the circular hearth, and means for rotating said hearth, said hearth having its upper surface of refractory material and said upper surface having a diameter greater than the inner diameter of the side wall.

In testimony whereof I have hereunto set my hand.

RANDAL E. TALLEY.
